Maxwell E. Sparrow

UNITED STATES PATENT OFFICE.

JOHN RODGERS, OF JAMAICA, NEW YORK.

ALBUM.

Application filed April 8, 1921. Serial No. 459,537.

To all whom it may concern:

Be it known that I, JOHN RODGERS, a citizen of the United States, and resident of Jamaica, in the county of Queens and State 5 of New York, have invented certain new and useful Improvements in Albums, of which the following is a specification.

This invention relates to improvements in albums.

10 The main purpose of this invention is to provide an album or portfolio particularly adapted to contain phonographic or like records of the disk type.

Another object of this invention is to 15 provide an album of the character stated above having a main binding element which is provided with comb-like teeth, said teeth being consecutively arranged and adapted to be bent over and successively secure in 20 pairs containers in the form of envelopes, the latter being adapted to be turned over from a bending line at a fixed spaced distance from their bound edge.

A further object is to provide means 25 whereby the album may be withdrawn from storage in a convenient manner.

Another purpose is to provide means for 30 distinguishing the serial number of the album from others of like kind which may be filed in connection with it.

These and other like objects, such as convenience in operation, cheapness of construction and neatness of appearance, are attained by the novel construction, combination 35 and arrangement of parts hereinafter described and shown in the accompanying drawings, forming a material part of this disclosure, and in which:—

Figure 1 is a top plan or edge view showing 40 an album made in accordance with this invention in a partially open or expanded position.

Figure 2 is a rear elevation or back view of the same.

45 Figure 3 is a fragmentary longitudinal sectional view taken on line 3—3 of Figure 2.

Figure 4 is an enlarged transverse sectional view taken on line 4—4 of Figure 2.

50 Figure 5 is a similar sectional view taken on line 5—5 of Figure 2.

Figure 6 is a plan view of the leaf securing means, the blank form being indicated by the broken lines.

55 Figure 7 is a side view of the same.

Figure 8 is a view showing a collection

of details used as one of the securing elements for the metallic plates.

Figure 9 is a similar view showing the parts comprising the other securing ele- 60

ment.

Figure 10 is a plan view of the blank from which the leaves of the album are 65 formed.

Stated briefly in general terms, the in- 70

vention comprises an album having relatively stiff covers between which are containers in the form of an envelope, the same being removably secured in pairs between the comb-like teeth of the main binding ele- 75

ment.

Each of the several envelopes or leaves are perforated and notched along their upper edges so as to facilitate the removal of 75

the record contained therein.

The binding elements are secured to the back of the album in a manner which permits of removal and also of identifying the particular album from others of the same kind.

80 Referring now to the drawings in detail, the numeral 15 designates a pair of relatively stiff, permanent covers, integrally connected at their rear longitudinal edges by the backing 16, this backing being reinforced or stiffened by the insertion of a metallic plate 17 provided with openings 18 and 18', through which pass securing devices as further on described. The ends of the metal plate 17, which in shape is that of an 85 elongated rectangle, are perforated with a plurality of openings 19 arranged in a transverse row and from the material between these openings extend rounded projections or fingers 17' which, as will be 90 afterwards noted, are bent over upon the plate and confine the envelope leaves in a releasably secure manner. The perforations prevent the leaves from tearing at the point of contact.

95 These containers consist of a blank 20 shown in detail in Figure 10, the same presenting essentially a rectangular contour, offset in diagonally opposite directions along the bending lines 21, forming extending 100 tabs 22 which, when the blank is folded on the vertical central bending line 23, constitute the outer vertical edges of the envelopes.

105 Other parallel bending lines 24 are arranged at a uniform spaced distance from the transverse center line 23, upon which the

envelope pages are normally folded. A longitudinal bending line 25, disposed at the center of the blank, constitutes the bottom of the envelope in a manner which will be 5 clearly understood.

The opposite or upper edges 26, which are open or unattached, contain curved recesses 27, the same being formed equally on both sides of the envelope permitting access to 10 the periphery of the disc enclosed between the parts of the element 20 when the container is formed.

Midway in the halves of the blank element 20 are circular openings 28 which permit the 15 reading of the labels on the records. Adjacent one of the bending lines 24, central of each of the sides of the blank 20, is an elongated rectangular opening 30, the material being entirely cut away, while on the opposite 20 sides the material is sheared along the lines 31 forming flaps 32 which when passed through the openings 30 are gummed and folded over, holding the two portions of the leaf in close adherence, while the tabs 22 are 25 similarly turned and secured over the material of the adjacent connected leaf portion in a manner which will be readily understood.

From the foregoing it will be seen that 30 each blank forms two complete envelopes or double leaves connected along the folding line 23 and between these leaves, at each end of the fold are entered the bent projections 17' holding the envelopes in close proximity 35 to the face of the plate 17, the adjacent envelopes being held in a similar manner.

In this way each pair of two complete envelopes is removably secured to the main binding element or plate 17 so that if one 40 pair becomes worn or torn it can be readily removed by bending back the corresponding bent projections 17' and another pair placed and secured in its stead.

The plate 17, which is preferably curved 45 arcuately in the direction transversely of its length, is held against the backing 16 in the following manner.

A grommet 35 is formed with oppositely disposed inturned lugs 36 adapted to receive 50 a circular tag 37 shaped to present a convex face on which is imprinted a numeral or like distinguishing character 38, as shown in detail in Figure 8, this tag being backed by a metal plate 39 containing a central perforation 40.

Passing through the perforation is the body of a stud 41, its head 42 being disposed between the tag 37 and plate 39, while its bifurcated extending ends 43 are spread and clinched after passing through the cover back 16 and the opening 18 in the plate 17 holding the several parts in fixed relation.

A somewhat similar grommet 45 having a flat flanged center 46 containing a single 65 perforation 47, is held in position by a fas-

tener element 48 passed through the opening 47, the cover back and the other opening 18', the ends of the fastener being clinched on the plate 17.

This fastener is formed with an enlarged 70 cylindrical head 49 in the opening of which is pivotally contained the ends of a pull 50, the same normally hanging pendant but capable of being raised to act as a handle by which the album may be conveniently manipulated in removing from its case. 75

From the foregoing it will be seen that a neat, commodious and convenient arrangement for containing records has been disclosed and as the number in each container 80 is relatively limited the distinguishing character will be found useful in selecting desired records from a stock of considerable magnitude.

By modifying the leaves incorporated in 85 the above described device, the latter may be readily adapted to hold postcards and the like.

While certain preferred embodiments of 90 this device have been shown and described it will be understood that changes in the form, arrangements, proportions, sizes and details thereof may be made without departing from the scope of the invention as defined in the appended claims. 95

Having thus described my invention what I desire to secure by Letters Patent and claim, is:

1. An album comprising a pair of covers 100 flexibly united to a backing, a plurality of envelope leaves, a stiffener for said backing provided at its opposite ends with a transverse row of perforations and bent projections separated at their base portions by said perforations and engaging between successive pairs of said leaves, and means for removably engaging said stiffener to the backing. 105

2. An album comprising a pair of covers flexibly united to a backing, a plurality of 110 leaves, a stiffener for said backing provided at both ends with a transverse row of perforations disposed between, and separating the base portions of a series of bent projections removably engaging between successive pairs of said leaves, and means for removably engaging said stiffener to the backing. 115

3. In an album, a plurality of pairs of envelope leaves each pair formed from a single blank, said envelope leaves having recesses on their upper edges and openings through the sides thereof, tabs extending from opposed sides adapted to be secured on opposite edges after folding the blank, other tabs adapted to pass through openings in the opposite sides and be secured thereto, and means for clamping said leaves within a cover. 120

4. An album comprising covers, a backing 125 and envelope leaves disposed between said

- covers, a stiffener extending coincident with said backing, means formed with said stiffener for securing said leaves, means for removably engaging said stiffener to said 5 backing, and means combined with said engaging means for distinguishing the album.
5. An album comprising a pair of covers, a main binding element provided at each end with a plurality of perforations arranged in a transverse row and comb-like teeth formed from the material extending between said perforations, envelopes formed 10 in pairs from single blanks and adapted to be folded upon a bending line at a fixed 15 spaced distance from the rear edge of each, said teeth being consecutively arranged and adapted to be bent over and successively secure each pair of said envelopes, and means for securing said binding element to said 20 covers.
6. An album, comprising a pair of stiff covers, a connecting element joining said covers, a plurality of envelope-like leaves open at their upper edges, said leaves being 25 made in pairs from single blanks, a metal strip extending adjacent the connecting element, a plurality of prongs at the ends of said strip, each opposed pair of prongs being folded to engage between a pair of leaves 30 to hold them in operative position, and removable means for clamping said strip to the connecting element.
7. An album, comprising a pair of stiff covers, a connecting element joining said 35 covers, a plurality of envelope-like leaves
- open at their upper edges, said leaves being made in pairs from single blanks, a metal strip extending adjacent the connecting element provided at its ends with a plurality of openings arranged in a transverse row, 40 and fingers formed from the material extending between the openings in said strip, each opposed pair of fingers being folded to releasably engage between a pair of leaves to hold them in operative position, and removable means for clamping said strip to the connecting element. 45
8. In an album, a pair of leaves formed from a single blank of substantially rectangular contour, said blank being folded longitudinally to produce sides, and then transversely at the center line, and being formed with creased bending lines spaced from 50 said transverse fold, tabs located before folding upon diagonally opposite end edges of the sides, each tab being folded and caused to adhere to the adjacent edge of the opposite longitudinal side, and the respective sides being cut to form in each a tab extending from one of said bending lines towards the central line, and an opening opposite the tab of the other side, said last-named tabs being passed through said openings and caused to adhere to the opposite 55 sides. 60

Signed at New York in the county of New York and State of New York this 31st day of March A. D. 1921.

JOHN RODGERS.
